[57] CLAIM

The ornamental design for a bottle, as shown and described.

DESCRIPTION

FIG. 1 is a top and left side perspective view of a bottle showing my new design;

FIG. 2 is a left side elevational view of the design shown in FIG. 1;

FIG. 3 is a right side elevational view of the design shown in FIG. 1;

FIG. 4 is a rear elevational view of the design shown in FIG. 1;

FIG. 5 is a front elevational view of the design shown in FIG. 1;

FIG. 6 is a top plan view of the design shown in FIG. 1; and,

FIG. 7 is a bottom plan view of the design shown in FIG. 1.

The broken lines in the drawings are for illustrative purposes only and do not form part of the claimed design.
